Term of patent 14 years

(Cl. D34—15)

FIG. 1

FIG. 2

FIG. 3

FIG. 4

Fig. 1 is a side elevation of a velocipede showing my new design, the characteristic feature residing in the portion shown in full lines;

Fig. 2 is an enlarged side elevational view thereof;

Fig. 3 is a perspective view corresponding to the content of Fig. 2, taken from a point above and to the rear; and

Fig. 4 is an enlarged fragmentary plan view thereof; Portions of the broken line showing of the velocipede have been omitted from the views for convenience of illustration.

I claim:

The ornamental design for a velocipede, substantially as shown and described.
